MACHINE FOR MAKING GROMMETS

William M. Lee, Kaneohe, Territory of Hawaii

Application May 22, 1945, Serial No. 595,215

4 Claims. (Cl. 57—21)

(Granted under the act of March 3, 1883, as
amended April 30, 1928; 370 O. G. 757)

1

This invention relates to machines for making grommets and more specifically to machines for forming grommets from continuous lengths of fibrous material.

Heretofore, it has been the practice to make grommets from lengths of fibrous material such as cotton rope by wrapping a length of the material in an open spiral on a mandrel and then placing the mandrel in the crotch between the thumb and the forefinger, wrapping the thumb and forefinger about the mandrel, and either pulling the mandrel in a direction to roll the helices of the fibrous material lengthwise thereof thereby to bring the entire length of material into substantially the same plane in the form of a ring or grommet, or by moving the hand in a direction to push the fibrous material along the mandrel thereby to roll it into grommet shape. This hand method of manufacture is tedious and slow, and hence, costly.

It is an object of this invention to provide a machine for carrying out the aforesaid method of making grommets from lengths of fibrous material which will be comparatively simple to operate and with which grommets may be manufactured at a rapid rate.

Accordingly, invention resides in a grommet making machine comprising a mandrel adapted to support a length of fibrous material in an open spiral, means adapted to substantially engage the mandrel at opposite sides thereof, means for moving the mandrel longitudinally progressively to feed the spirally arranged fibrous material toward the first named means, and means for moving the first named means in a direction to cause its surfaces to roll the open helices of the fibrous material together into a grommet on the mandrel. More specifically, the mandrel is provided with means for retaining the fibrous material thereon, an air operated piston is connected to the mandrel to reciprocate the same longitudinally, and a pair of grooved rubber rolls are arranged to substantially engage the opposite sides of the mandrel, the rolls being rotated in a direction opposite to the direction of movement of the mandrel by air operated motors. In practice, the terminal end of a length of fibrous material is given a turn about the mandrel close to the rubber rolls and is then wound in an open spiral along the mandrel, that is, away from the rolls, the end of the fibrous material which is connected to the source of material being held taut, hence, there is associated with one of the aforesaid rolls, means for severing the finished grommet from the source of fibrous material.

2

The invention will now be described with reference to the accompanying drawing, in which:

Fig. 1 is a schematic view of the machine for forming grommets showing a length of cotton rope wound in an open spiral thereon;

Fig. 2 is a detail of one of the rubber rolls showing a groove in its peripheral surface;

Fig. 3 is a perspective view of the grommet making machine;

10 Fig. 4 is a finished grommet; and

Fig. 5 is a detail view showing a mandrel.

Referring to Fig. 1, the grommet making machine is shown schematically as consisting of a mandrel 10, a pair of rolls 12 and 14 arranged to substantially engage the mandrel at opposite sides thereof, a cross head 16 for reciprocating the mandrel in a longitudinal direction between the rolls and a pair of shafts 18 and 20 for effecting rotation of the rolls in a direction which is opposite to the direction of movement of the mandrel

15 during the grommet forming operation. In manufacture of a grommet with the apparatus outlined above, a continuous length 22 of cotton rope, sliver, yarn or string or any other fibrous material whether of wool, paper fiber or cellulose fiber

20 is given a turn around the mandrel adjacent to the rolls 12 and 14 to secure it to the mandrel and then is wrapped in an open spiral downwardly from the rolls toward the end of the mandrel and

25 is held taut while the machine goes through a cycle of forming a grommet such as is illustrated in Fig. 4. The forming operation consists of imparting longitudinal movement to the mandrel with respect to the rolls 12 and 14 to draw the open spiral of cotton rope toward the rolls 12 and 14. As the mandrel moves through the rolls, the oppositely moving surfaces of these rolls tend to scuff or roll the cotton rope along the surface of the mandrel and to bring the open helices of

30 the rope into substantially the same plane, thereby to form a circular or grommet shaped member. More specifically, the machine as shown in Fig. 3, in perspective, comprises a post 24 secured in an upright position to a base 26, the post having a bent over terminal end 28 to which is attached a cylinder 30.

35 Within the cylinder there is arranged to reciprocate a piston (not shown) to which the mandrel 10 is removably attached for reciprocal motion in a substantially vertical position by air pressure, for example, supplied by hose connection 35. Projecting laterally from opposite sides of the cylinder 30 are a pair of arms 32 to which are attached driving means 34,

40 the specific means shown herein, consisting of air operated motors with hose connections, as indicated in Fig. 1. The cylinder 30 is provided with a

45

cated at 37 and 38. The driving means 34, however, may be electric motors or any other type of means suitable for the purpose of driving the shafts 18 and 20. The rolls 12 and 14 preferably are formed of rubber and are grooved, as shown in Fig. 2, so as to embrace the mandrel. These rolls, however, may be made of any suitable material and may be covered with leather or fabric. While a pair of motors have been shown for driving the rolls 12 and 14, it is also within the scope of the invention to use a single motor and suitable gearing to drive the two rolls or if desired, foot power operated means may be employed for driving the rolls. While it is possible to employ short lengths of fibrous rope in making grommets by securing the rope at both ends to the mandrel, it is preferable to use a continuous length of material and for this reason, there is provided means for severing the finished grommet from the source of supply when it has been rolled into shape. As illustrated herein, this is provided for by a disc shaped cutting member 36 mounted on the shaft of one of the rolls 12 or 14 preferably for rotary movement therewith, and against which the cotton rope may be held to sever it at the end of the grommet forming operation. In order to collect the grommets as they are pushed off the end of the mandrel, a container 38 is placed beneath the mandrel on the stand 26 into which they will fall. As indicated, the cutter 36 is of larger diameter than the adjacent roll 14 and is disposed in a plane substantially parallel to and adjacent to the plane which includes said rolls and mandrel. The cutter is thus disposed to readily sever the rope as the mandrel moves between the rolls at the end of the grommet forming operation.

The mandrel 10 is shown as cylindrical in cross section, however, it is possible to make it of any cross section desired and in order to improve the rolling action, which compacts the fibers and twists the helices together to form the grommet, it is desirable to roughen the surface of the mandrel to some degree, for example, by knurling, grooving or by having a coating on the surface of the mandrel which will afford some resistance to sliding of the rope on the surface of the mandrel. Such a coating preferably is of rubber Fig. 5, but may be leather, fabric or a suitable paint or lacquer.

In operating the machine to form grommets, a continuous length of cotton rope or analogous material is secured to the mandrel 10 at its free end by giving it a twist or suitable lap turn in the known manner around the mandrel adjacent to the rolls 12 and 14 and then wrapping it in an open spiral away from the rolls toward the end of the mandrel. The rope running from the end of the mandrel to the source of supply is held taut, whereupon the operator actuates means, not shown, acting through air hose connections, as indicated at 35 and 37, 38 for causing the piston to move upwardly in the cylinder 30 and hence the mandrel to be withdrawn from between the rolls 12 and 14 and from simultaneously causing the rolls to rotate in directions so that their surfaces move in directions opposite to the movement of the mandrel. As soon as the mandrel reaches a point between the rolls where the action of the rolls has formed the grommet and forced it nearly to the end of the mandrel on its up stroke, the rope being held taut is thus brought into position against the cutting means 36, thereby to sever the cotton rope and the completed grommet then drops into the container 38. The ma-

chine is then stopped and the rolls cease turning, and the spindle or mandrel drops back to its lower position ready for forming the next grommet.

5 The invention described herein may be manufactured and used by or for the Government of the United States of America for governmental purposes without the payment of any royalties thereon or therefor.

10 What is claimed is:

1. A grommet making machine comprising a mandrel adapted to support a length of fibrous material in an open spiral, rolls disposed adjacent the mandrel on opposite sides thereof, means for moving the mandrel longitudinally progressively to feed the spiral of fibrous material toward and between the rolls and mandrel, means for rotating the rolls in directions to cause a grommet to be rolled from said fibrous material between the surfaces of the rolls and the mandrel, and a cutting member mounted on said machine and disposed adjacent to one of said rolls, said cutting member being so mounted on said machine as to cut the fibrous material on the grommet forming stroke of the mandrel, thereby severing the completed grommet from the remaining fibrous material.

2. A grommet making machine comprising a mandrel adapted to support a length of fibrous material in an open spiral, rolls disposed adjacent the mandrel on opposite sides thereof, means for moving the mandrel longitudinally progressively to feed the spiral of fibrous material toward and between the rolls and mandrel, means for rotating the rolls in directions to cause a grommet to be rolled from said fibrous material between the surfaces of the rolls and the mandrel, and a cutting member mounted on said machine and disposed adjacent to one of said rolls, said cutting member being so mounted on said machine as to cut the fibrous material on the grommet forming stroke of the mandrel, thereby severing the completed grommet from the remaining fibrous material, said cutting member being mounted on the shaft of said adjacent roll.

3. A grommet making machine comprising a mandrel adapted to support a length of fibrous material in an open spiral, rolls disposed adjacent the mandrel on opposite sides thereof, means for moving the mandrel longitudinally progressively to feed the spiral of fibrous material toward and between the rolls and mandrel, means for rotating the rolls in directions to cause a grommet to be rolled from said fibrous material between the surfaces of the rolls and the mandrel, and a cutting member mounted on said machine and disposed adjacent to one of said rolls, said cutting member being so mounted on said machine as to cut the fibrous material on the grommet forming stroke of the mandrel, thereby severing the completed grommet from the remaining fibrous material, said cutting member comprising a cutting disc of larger diameter than the adjacent roll and being fixedly mounted on the shaft of the adjacent roll for rotation with said roll.

4. A grommet making machine comprising a mandrel adapted to support a length of fibrous material in an open spiral, rolls disposed adjacent the mandrel on opposite sides thereof, means for moving the mandrel longitudinally progressively to feed the spiral of fibrous material toward and between the rolls and mandrel, means for rotating the rolls in directions to cause a grommet to be rolled from said fibrous material between the surfaces of the rolls and the mandrel, and

a cutting member mounted on said machine and disposed adjacent to one of said rolls, said cutting member being so mounted on said machine as to cut the fibrous material on the grommet forming stroke of the mandrel, thereby severing the completed grommet from the remaining fibrous material, said cutting member being disposed in a plane substantially parallel to and adjacent to the plane including said rolls and mandrel.
